DESIGN FOR A FLOOR LAMP

Leroy C. Doane, Essex, Conn., assignor to The
Sight Light Corporation, Deep River, Conn., a
corporation of Connecticut

Application June 7, 1946, Serial No. 130,494

Term of patent 14 years

(Cl. D48—20)

To all whom it may concern:

Be it known that I, Leroy C. Doane, a citizen of the United States, residing in Essex, county of Middlesex and State of Connecticut, have invented a new, original, and ornamental Design for a Floor Lamp, of which the following is a specification, reference being had to the accompanying drawing, forming part thereof.

Figure 1 is a perspective view of a floor lamp showing my new design.

Figure 2 is a plan view of the lamp shown in Fig. 1.

Figure 3 is a side elevation of the lamp shown in Fig. 1, a part of the standard being broken away.

I claim:

The ornamental design for a floor lamp, substantially as shown.

LERoy C. DOANE.
